UNITED STATES PATENT OFFICE.

NICHOLAS A. HULL, OF PERU, INDIANA.

DESIGN FOR A SEWING-MACHINE CASE.

SPECIFICATION forming part of Design No. 16,040, dated April 14, 1885.

Application filed February 18, 1885. Serial No. 156,310. Term of patent 3½ years.

To all whom it may concern:

Be it known that I, NICHOLAS A. HULL, of the city of Peru, in the county of Miami and State of Indiana, have originated and invented a new and useful Design for Sewing-Machine Cases; and I do hereby declare that the following is a full, clear, and exact description thereof, reference being had to the accompanying photograph, forming a part of this specification.

In the photograph is represented a perspective view of a sewing-machine provided with a case constructed according to my design.

In the photograph, A is the case, having at its front a main panel, B, and raised center panel, C. The panel C is surrounded by a border consisting of a series of beads and grooves, forming a convex and concave border, *a*, being separated from the center panel, C, by a bevel cut, *b*, which is deeper than the concave cut in the border. This border *a* crosses at the corners, and forms around the panel C eight distinct and smaller panels, the panel C being beveled on the edges, as shown, the bevels on the center panel and border panels extending on a straight line and parallel with each other.

The case A, above the main panel B, has a fringed rail, *c*, the fringe being cut entirely across the edge of the rail.

The case A has rounded corners *d*, with transverse raised beads *e* in center and at both

ends thereof, and has a Gothic top, D, molded with a series of beads, *f*, in center, and large concave on each side, as shown at *g*, all running parallel with the top of the case.

The ends of the case A are provided with sunken end panels, *h*, extending to the top edge of the rounded corners *d*, and on a line with the lower edge of the front and back top molding.

What I claim is—

1. The design for the ornamentation of sewing-machine cases, the same consisting of the Gothic top D, having a series of beads, *f*, and fringed rail *c*, as shown and described.

2. The design for the ornamentation of sewing-machine cases, the same consisting of the main panel B, comprising the center panel, C, surrounded by the border *a*, formed of a series of beads crossing each other at the corners, as shown and described.

3. The design for the ornamentation of sewing-machine cases, the same consisting of the Gothic top D, having a series of beads, *f*, and fringed rail *c*, and the panel C, surrounded by the beaded border *a*, as shown and described.

In testimony that I claim the foregoing as my own I affix my signature in presence of two witnesses.

NICHOLAS A. HULL.

Witnesses:

JAMES M. BROWN,
JOHN H. REAM.
